(57) **CLAIM**

The ornamental design for a door strike, as shown and described.

DESCRIPTION

FIG. 1 is a perspective view of a first embodiment of the door strike according to the present invention;

FIG. 2 is an end elevation of the door strike shown in FIG. 1;

FIG. 3 is a front elevation of the door strike shown in FIG. 1;

FIG. 4 is a rear elevation of the door strike shown in FIG. 1;

FIG. 5 is a top plan view of the door strike shown in FIG. 1;

FIG. 6 is a bottom plan view of the door strike shown in FIG. 1;

FIG. 7 is a perspective view of a second embodiment of the door strike according to the present invention;

FIG. 8 is an end elevation of the door strike shown in FIG. 7;

FIG. 9 is a front elevation of the door strike shown in FIG. 7;

FIG. 10 is a rear elevation of the door strike shown in FIG. 7;

FIG. 11 is a top plan view of the door strike shown in FIG. 7; and,

FIG. 12 is a bottom plan view of the door strike shown in FIG. 7.

The broken lines are shown for illustrative purposes only and form no part of the claimed design.
